UNITED STATES PATENT OFFICE.

MIKE MACURA, OF HASTINGS-ON-HUDSON, NEW YORK.

BURGLAR ALARM.

Application filed July 18, 1923. Serial No. 652,323.

To all whom it may concern:

Be it known that I, MIKE MACURA, a citizen of Czechoslovakia, residing at Hastings-on-Hudson, in the county of Westchester and 5 State of New York, have invented certain new and useful Improvements in Burglar Alarms, of which the following is a specification.

This invention relates to new and useful 10 improvements in burglar alarms. An important object of the invention is to provide an alarm that is adapted for giving warning of the unauthorized opening of a door by a burglar or other intruder.

15 A further object of the invention is to provide an alarm that is adapted for being positioned upon the floor of a room in proximity to a closed door in such a manner that when the door is opened the alarm will be 20 operated.

Other objects and advantages of the invention will be apparent during the course of the following description.

In the accompanying drawing forming a 25 part of this specification and in which like numerals are employed to designate like parts throughout the same,

Figure 1 is a side elevational view of the burglar alarm properly positioned in respect 30 to the fragmentary portion of a door that is shown in vertical section,

Figure 2 is a top plan view of the alarm shown in Fig. 1 with the door shown upon line II-II of Fig. 1, and

35 Figure 3 is a vertical sectional view taken on line III-III of Fig. 1.

In the accompanying drawing, wherein for the purpose of illustration is shown a preferred embodiment of this invention, the 40 numeral 5 designates the floor of a room having a door sill 6 suitably mounted thereon in operative relation with the door 7.

The alarm embodying this invention consists of a substantially wedge-shaped frame 45 portion that is designated in general by the numeral 8 and is formed from a sheet of metal that is properly cut and bent to provide a substantially rectangularly-shaped flat base portion 9 which is cut at desired 50 points to form the depending spears or points 10 which are employed for connecting the wedge-shaped frame to the substantially rectangularly-shaped block of rubber 11. One end of this flat base portion 55 is bent to extend at an obtuse angle to the said base portion 9 and is designated by the

numeral 12. This angularly arranged portion 12 is suitably formed or molded to provide the longitudinally extending rib 13 which is employed for reinforcing the said 60 portion 12. The upper end of this angularly arranged top portion 12 is bifurcated for forming the downwardly inclined end portion 14 and for forming the substantially L-shaped depending leg 15. The opposite end 65 of the base portion 9 is bent upon itself, as at 16 and is then bent at right angles to the base portion 9 for providing a vertically extending bracket portion 17 which is formed with an integral flange 18 to which is bolted the bicycle bell 19 which is provided with the usual operating button 20. The remaining end of this sheet or strip of metal is bent to underlie the angularly arranged top portion 12 for forming a resilient stop for the 70 same which I will designate by the numeral 21. The free end of this stop 21 is arcuately bent, as at 22 for providing a leg that will strike the upper surface of the base plate 9 when moved thereagainst. It will be seen 75 by inspecting the various figures that the L-shaped depending leg 15 will normally engage the bell operating button 20.

When the burglar alarm is positioned in close proximity to a door with the rubber 80 block 11 frictionally engaging the floor, as shown in Fig. 1, the movement of the door 7 to the dotted line position shown will cause the lower transverse edge of the said door to strike the angularly arranged top 85 portion 12 of the frame 8. This striking of the top portion 12 will cause the same to be forced downwardly in respect to the base 9 for causing the depending L-shaped leg 15 to move the bell operating button 20 downwardly for sounding the said bell. Should the portion 12 be forced downwardly until it engages the stop 21, the resiliency of this stop 90 will aid in returning the angularly arranged top portion 12 to its normal position. The 95 arcuate end 22 of the stop 21 will prevent the angularly arranged top portion 12 from moving too great a distance downwardly in the direction of the base plate 9.

It is to be understood that the form of this 100 invention herewith shown and described is to be taken as the preferred example of the same, and that various changes in the shape, size, and arrangement of parts may be resorted to without departing from the 110 spirit of the invention or the scope of the subjoined claim.

Having thus described the invention, I claim:—

In an alarm of the type described, a base plate having depending prongs, a rubber block secured to said base by said prongs, an angularly arranged top portion carried by one end of said base portion, a bracket member carried by the opposite end of said base, a bicycle bell carried by said bracket having an operating button projecting therefrom, a depending leg carried by the free end of said

angularly arranged portion adapted for engaging said operating button for sounding said bell when the angularly arranged portion is moved in the direction of said base portion, and a movement limiting arm carried by said bracket member for preventing too great a downward movement of said angularly arranged portion. 15

In testimony whereof I affix my signature.

MIKE MACURA.
